R. BEAN

REFACING TOOL

Filed Oct. 7, 1920

Inventor
Roscoe Bean

By
Ged B. Billman
Attorney

UNITED STATES PATENT OFFICE.

ROSCOE BEAN, OF BEREAL, OHIO.

REFACING TOOL.

Application filed October 7, 1920. Serial No. 415,371.

To all whom it may concern:

Be it known that I, ROSCOE BEAN, a citizen of the United States, residing at Berea, in the county of Cuyahoga and State of Ohio, have invented certain new and useful Improvements in Refacing Tools, of which the following is a specification.

My invention relates to improvements in refacing tools, and more particularly to that 10 class or type adapted to reclaim worn or imperfect surfaces or bearings by a cutting or abrasive action thereby restoring to the original contour or fit.

The present embodiment of the invention 15 is particularly designed and adapted for use in the reclaiming or reseating of the valve seats of ordinary "poppet" valves of internal combustion engines.

The primary object is the provision of a 20 generally improved tool of this class which will be exceedingly simple in construction, cheap of manufacture, and efficient in use.

A further object is the provision of an 25 improved tool of this class in which improved guide and driving spindles are provided in connection with an improved cutter carrier provided with multiple faced reversible cutters, said guide and driving spindles being so arranged and disposed 30 relative to each other and to the cutter carrier with its cutters that the bearing surface or face of the valve seat will be cut or reclaimed at a properly angled and centralized position 35 relative to the common axial plane of the cavity or valve seat.

A still further object is the provision of 40 an improved rotary cutter carrier together with an improved form of multiple faced reversible cutters and means for supporting said cutters with the active cutting faces thereof inclined at acute angles to the radial planes extending thru the axis of rotation of the rotatable cutter whereby such cutting faces form their own clearance at 45 the rear of the cutting edges and the surface being reclaimed so that all edges of the faces of the reversible cutters may be utilized.

With the above mentioned and other ends 50 in view, the invention consists in the novel construction, arrangement, and combination of parts, hereinafter described, illustrated in some of its embodiments in the accompanying drawings, and particularly pointed out in the appended claims.

Referring to the drawings, forming a part

of this specification, Figure 1 is a side elevation of a tool constructed in accordance with this invention.

Fig. 2, a top plan or end view of the same.

Fig. 3, an end view of the under or cutting face portion of the same.

Fig. 4, a sectional view of the cutter carrier and the movable guide and driving spindles thereof, and illustrating in particular the manner of mounting and securing 65 the latter thereon.

Fig. 5, a fragmentary cross sectional view of the cutter carrier and one of the reversible cutters, illustrating the manner of mounting the latter.

Fig. 6, a perspective view of one of the multiple faced reversible cutters, detached.

Fig. 7, a side elevation illustrating the application of the improved tool as a refacing or reclaiming tool in connection with a valve 75 seat of an engine.

Fig. 8, a side elevation of a modified form of cutter carrier, and a modified means of mounting the reversible cutters thereon.

Fig. 9, a view of the under or face side 80 of the cutter carrier, the driving and guiding spindles being removed.

Similar numerals of reference designate 85 like parts thruout all the figures of the drawings.

The improved refacing tool comprises a cutter carrier 1, upon which the improved cutters hereinafter described are mounted, said cutter carrier being adapted to be rotated or driven by means of a driving spindle or shank 2, and being preferably provided with a guide or pilot spindle 3.

The driving spindle or shank 2, may be operated in any suitable and convenient manner, as for example,—by means of a removable cross arm or rod 4, mounted in a suitable opening in the top of the spindle 2, as shown in Fig. 1 of the drawings, or by means of a suitable wrench such as a brace wrench 5, as shown in Fig. 7 of the drawings.

As a means of removably mounting and securing the cutter carrier 1, upon the driving spindle or shank 2, the latter is preferably provided with a rounded reduced portion 2^a, terminating in an angular or square shaped portion 2^b, adapted to be fitted or seated in a similarly shaped opening in the head or carrier 1, as shown most clearly in Fig. 4 of the drawings. The angular por-

2
tion 2^b, will prevent the carrier 1, from moving circumferentially on the driving spindle 2, when the latter is operated, and as a means of securing the carrier in seated position the angular portion 2^b, terminates in a threaded extension provided with a securing nut 6.

As a means of securing the pilot spindle or guide shank 3, the driving spindle 2, is provided with an opening 2^c, within which the spindle 3, is removably mounted, and if desired the top of the spindle 3, may be provided with an annular groove 3^a, within which may be seated a securing screw 7.

15 The improved cutters 8, are adapted to be reversibly and interchangeably mounted upon the cutter carrier 1, as hereinafter more fully described, said cutters being provided with a plurality of faces 8^a, said faces 20 8^a, when the cutters are mounted as hereinafter described, forming cutting edges 8^b.

As a means of adapting the improved tool for use as a reseating tool to reclaim or reform the annular seat 9^a, of the valve 25 portion of an ordinary internal combustion engine, as illustrated in Fig. 7 of the drawings, the cutter carrier 1, is preferably in the form of an inverted truncated cone conforming substantially to the form of the ordinary valve head used in this class of valves, and as a means of securely mounting and holding the cutters 8, in proper position so that all the cutting edges 8^b, (in the present instance eight in number), may be 30 utilized, the cutter carrier is provided about its outer periphery with a plurality of cutter receiving recesses 1^a, said recesses being either in the specific form shown in Figs. 1 to 5, inclusive, of the drawings, to receive 35 and carry the cutters in a relatively flat position with respect to the face of the cutter carrier, or in the specific form of vertically extending notched recesses 1^b, to receive and carry the cutters 8 in a relatively 40 vertical position, as shown in Figs. 8 and 9 of the drawings.

As a means of removably securing the cutters within the notched recesses 1^a and 1^b, respectively, the cutters 8 may be provided 50 with central openings 8^c, adapted to receive and contain attaching elements 10, in the specific form of screws, as shown, said attaching elements being screwed into suitable threaded openings in the cutter carrier 1.

It will be seen that the supporting faces of the cutter receiving recesses 1^a and 1^b, are arranged in such relation to the surface to be recut or reclaimed, such for example as the seat 9^a, and to the longitudinal axial center of the pilot spindle 3 and the valve stem opening 9, that the active cutting faces 8^a, will be inclined at acute angles to the radial planes extending thru the axis 65 of the rotary cutter carrier or tool and the

common axis of the cavity or seat to be reclaimed, whereby such cutting faces form their own clearance at the rear of the cutting edges 8^b and relative to the direction of movement of such cutting edges 8^b, and the 70 surface being cut or reclaimed by such active cutting edges.

Upon reference to Figs. 2 and 9 of the drawings, it will be seen that the lines *a*—*a* indicating the radial planes extending 75 through the axis of the rotary cutter carrier and the common axis of the seat being reclaimed bisect the cutting edges 8^b, formed by the faces 8^a, (in accordance with the direction of rotation of the cutter carrier) and that such faces are inclined at acute angles to the radial planes indicated by such lines.

In the form of the mounting of the cutters shown in Figs. 1 to 5, inclusive, of the drawings, such cutters are adapted to act equally well in either direction of rotation of the cutter carrier thru the driving spindle 2, while in the form shown in Figs. 8 and 9, a rotation in one direction is effected. 90 If desired, however, one side or the other of the active cutting faces may be elevated slightly above the opposite, so that one cutting edge only is used thru the medium of a wedge-shaped piece or filler plate 11, inserted between the base of the cutter and the seat portion of the groove or cutter receiving recess 1^a, as shown most clearly in Fig. 5 of the drawings.

From the foregoing description, taken in 100 connection with the accompanying drawings, the operation and advantages of my invention will be readily understood.

Having thus described some of the embodiments of my invention, without having attempted to set forth all the forms in which it may be made, or all the modes of its use, what I claim and desire to secure by Letters Patent, is,—

1. In a bearing surface reclaiming tool, 110 a rotatable cutter carrier provided with a removable pilot or guide spindle, and a plurality of interchangeable multiple faced reversible cutters mounted thereon whereby the active cutting faces conjointly form 115 cutting edges for rotation of the cutter carrier in either direction and clearance at the rear of the cutting edge being used.

2. In a bearing reclaiming tool, a rotatable cutter carrier, and a multiple faced 120 reversible cutter carried thereby with its active cutting faces inclined at acute angles to the radial planes of the axis of rotation whereby clearance is formed at the rear of the cutting edges and between the cutting 125 face and surface being reclaimed so that all cutting edges of the faces of the reversible cutter may be utilized.

3. In a bearing surface reclaiming tool, a rotatable cutter carrier provided with re- 130

- movable driving and pilot spindles, and multiple faced cutters, and means for securing the latter thereon in predetermined positions whereby the active cutting faces 5 conjointly forming cutting edges may be alternately brought into service for rotation of the cutter carrier in either direction.
4. In a bearing surface reclaiming tool, a rotatable cutter carrier provided with axial driving and guide spindles, multiple faced cutters mounted thereon with the active cutting faces conjointly forming cutting edges, and means for adjusting and bringing such cutting edges into operation at one side or the other for rotation of the cutter carrier in a corresponding direction and affording clearance at the rear of the cutting edge being used.
- 10 In testimony whereof I have affixed my signature.

ROSCOE BEAN.
